INSTRUMENT PANEL SWITCH

James Robert Ferguson, Huntington Woods,
Mich., assignor to Packard Motor Car Com-
pany, Detroit, Mich., a corporation of Michigan

Application October 4, 1947, Serial No. 777,920

4 Claims. (Cl. 175—298)

1

This invention relates to a switch actuating mechanism, and more particularly to a plurality of separate switches mounted as a subassembly, and adapted to be actuated by a plurality of separately operable control members associated therewith.

In the automotive industry a number of switches are employed to control various elements of the car such for example as the headlights, heater, defroster, transmission, fog lights, ventilators, etc. It has been customary to actuate these switches by control members secured to a movable portion of the switch, and positioned in a readily accessible place on an instrument panel so that the driver can readily manipulate them. It has been difficult to position the switches in such a manner that the control members can be placed on the instrument panel in the most convenient locations, and the switches are quite inaccessible when repair or replacement is necessary.

An object of this invention is to provide separate switch and switch actuating sub-assemblies that can be bench assembled and readily positioned in a motor vehicle.

A further object of the invention is to provide a switch and switch actuating sub-assembly having a plurality of switches mounted on a bracket, for assembly into a vehicle body.

Another object of the invention resides in the provision of a switch actuating mechanism having a plurality of selectively operable push buttons to actuate a series of switches carried by a bracket adapted to be mounted as a sub-assembly in an article of manufacture.

Yet a further object of the invention is to provide a series of aligned push buttons mounted on a panel to actuate a series of correspondingly placed switches of the push and return type, and wherein adjustable switch actuating motion transmitting means are interposed between the panel and the push buttons to permit aligning the push buttons with the panel.

Still another object of the invention is to provide a switch assembly having a bracket adapted to receive a plurality of plunger type switches of the push and return type and a push button type switch actuating mechanism secured to the bracket, and having an adjusting mechanism between the push buttons and the switches whereby the push buttons may be separately adjusted to align them with each other.

Other objects of this invention will appear in the following description and appended claims reference being had to the accompanying draw-

2

ings forming a part of this specification wherein like reference characters designate corresponding parts in the several views.

Fig. 1 is a sectional view partly in elevation, of a switch and actuating assembly embodying this invention, and taken substantially on the line 1—1 of Fig. 2 looking in the direction of the arrows.

Fig. 2 is a front view of the assembly.

Fig. 3 is a fragmentary sectional view taken substantially on the line 3—3 of Fig. 1, looking in the direction of the arrows.

Fig. 4 is a fragmentary front view of the switch carrying bracket.

Fig. 5 is an exploded view illustrating the push button adjusting mechanism.

It is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring now more particularly to the drawings it will be noted that a channel shaped bracket 10 having upper and lower horizontally extending flanges 12 and 14 is provided to receive a plurality of spaced switches 16. The switches 16 may be of any suitable type, but are illustrated as being of the push and return type having plungers 18 adapted to actuate the switch mechanism. For example when the plunger 18 is actuated once, the switch is moved to the "on" position, and when the plunger is actuated again the switch is moved to the "off" position. Where a switch having more positions is required to control a device having several ranges or speeds of operation, such as a heater or a defroster, the plunger 18 may be successively actuated to turn the switch on, and progress through the various speed or range positions and then move the switch mechanism to the "off" position.

The switches 16 are illustrated as being rectangular in shape, and having threaded projections 20 surrounding the plungers 18 and adapted to project through spaced apertures 22 in the bracket 10. The lower flange 14 of the bracket is cut away as illustrated at 24 to receive the ends of the switches 16, and to provide spaced projecting flanges on opposite sides of the switches to prevent the switches from cocking or moving angularly in the apertures 22 in

the bracket. Spacers 26 surrounding the threaded projections 20 are interposed between the switches 16 and the bracket 10 and nuts 28 threaded on the projections 20 are provided to clamp the switches 16 to the bracket 10.

The switches 16 are provided with terminal posts 30 and 32 adapted to receive electrical leads 34 and 36.

It will of course be apparent that if desired the switches 16 may be valves to control the flow of fluid under pressure to actuate any desired mechanism, such for example to raise and lower the top of a convertible automobile, to actuate windows, or control the position of a movable seat.

A panel 38 having a plurality of selectively operable switch controlling members such as push buttons 40 having a symbol 41 thereon indicating the element controlled by its associated switch may be secured to the bracket 10 in any suitable manner as by screws 42. The screws may project through apertures 44 in the bracket 10 and extend into threaded bosses 46 secured to or integral with a vertical wall 48 of the panel 38. The wall 48 is spaced from the front face 50 of the panel 38, and is connected thereto through an upper horizontally extending wall 52. The wall 48 carries a lower horizontally extending wall 54 spaced from the wall 52 to define a channel 56 therebetween to receive the push buttons 40.

The lower wall 54 is provided with spaced rectangular shaped guides 58 extending from its front face 60 to the vertical wall 48. The push buttons 40 are formed with rectangular shaped body sections adapted to project into the channel 56 for movement therein toward and away from the vertical wall 48. The bottom walls of the push buttons are cut away to provide spaced longitudinally extending grooves 62 and 64 on their opposite sides as illustrated in Fig. 2 to receive the guides 58 to induce substantially straight line movement of the push buttons thereby preventing cocking or binding. Leaf springs 65 carried by the guides 58 are provided to ride in the grooves 62 and 64 of the push buttons to urge them upwardly into engagement with the upper wall 52 to prevent the push buttons 40 from rattling in the channel 56. A felt pad 67 positioned on one side of each push button is provided to maintain the push buttons in spaced relation to prevent rattling resulting from transverse movement of the push buttons.

Motion transmitting means carried by the push buttons 40 are provided to actuate the plungers 18, and to vary the adjusted position of the rounded front ends 66 of the push buttons with reference to the front face 50 of the panel 38 to permit aligning the push buttons with each other.

One illustrative example of such motion transmitting means includes a plurality of studs 68 projecting through apertures 70 in the wall 48, carried by the panel 38, and having heads 72 interposed between the wall 48 and the ends of the plungers 18. The studs are threaded into the push buttons 40, springs 74 surrounding the studs being interposed between the wall 48 and the push buttons 40 as illustrated to yieldingly urge the push buttons from a switch actuating position towards a switch return or released position. A washer 76 is interposed between each of the springs 74 and its associated push button 40, and preferably has a non-circular aperture 78 to receive a flattened side of the stud 68 to

prevent the stud from turning relative to the washer. The washer 76 is formed with a V-shaped notch 80 to engage in grooves 82 formed in a threaded boss 84 of each of the push buttons 40 to prevent the stud 68 from turning in its associated push button until sufficient force is exerted thereon to compress the spring 74 sufficiently to permit the V-shaped notch 80 formed in the washer 76 to disengage one aligned pair of grooves 82 in the boss 84 of the push button. The assembly is thus securely maintained in adjusted position.

Each of the switches 16 may be actuated by pushing its associated push button 40 inwardly to the switch actuating position whereupon the head 72 of the stud 68 transmits movement of the push button to move the plunger 18 to actuate the switch. The spring 74 urges the push button to the switch return position when the push button is released.

To align the push buttons 40 with reference to the front face 50 of the panel 38 the studs 68 are rotated to vary the distance between their associated push buttons and the vertical wall 48, the washers 76 locking the push buttons in any adjusted position. It will be noted that the heads 72 of the studs 68 are urged into contact with the wall 48 by the springs 74 in the switch return position, a washer 86 of sound absorbing material such as felt or cork being interposed between the head 72 of each of the studs 68 and the wall 48 to prevent noise as the plunger 40 is moved to the switch return position by its associated spring 68. Adjustment of the spacing of the push buttons therefore, does not disturb the operative relation between the heads 72 of the studs 68 and the plungers 18 of the switches 16.

It will be apparent that a sub-assembly consisting of the switches 16 mounted on the bracket 10, and the panel 38 having the push buttons 40 mounted thereon may be secured together and adjusted to properly align the front ends 66 of the push buttons with reference to the front face 50 of the panel before being assembled into the vehicle. Also before assembly into the vehicle the appropriate leads 34 and 36 from the wiring harness are preferably connected to the respective terminal posts 30 and 32 of switches 16. The complete sub-assembly thus formed is positioned in place, and is secured to the vehicle body by suitable fastening means (not shown) securing the bracket 10 and panel 38 to the body. If desired the bracket 10 having the switches 16 mounted thereon may be assembled in the vehicle as one sub-assembly, and the panel 38 having the push buttons 40 mounted thereon may be assembled in the vehicle as a separate sub-assembly. To repair or replace any of the switches 16 the panel 38 having the push buttons 40 may be removed as a unit to permit free access to the switch assembly. It will also be apparent that the individual switches 16 may be readily removed from the bracket 10 by removing their respective nuts 28 to release the switch from the bracket. The switch can be repaired or replaced by a new one and reassembled with reference to the bracket 10 without removing the bracket or the panel 38 from the vehicle.

It is of course apparent that the bracket 10 holding the switches 16 may be of any desired shape, since it is not necessary that the switches or the push buttons for actuating them be positioned in a straight line.

It will be understood that various forms of

the invention other than those described above may be used without departing from the spirit or scope of the invention.

I claim:

1. In a switch actuating mechanism the combination with a plurality of separate switches of the push and return type having movable plungers, a bracket supporting said switches with their plungers in parallel relation, of a panel spaced from the bracket and having a channel shaped portion spaced from and extending parallel to said bracket, a plurality of separate push buttons slidably mounted in the channel and movable between switch actuating and switch return positions, guide means between the push buttons and the channel, adjustable actuating means carried by the push buttons and extending through the channel in alignment with the switch plungers, and yielding means between the push buttons and the channel to urge the push buttons to the switch return position.

2. In a switch actuating mechanism the combination with a plurality of separate switches of the push and return type having movable plungers, a bracket supporting said switches with their plungers in parallel relation, of a panel spaced from and carried by the bracket and having a channel shaped portion, a plurality of separate push buttons slidably mounted in the channel and movable between switch actuating and switch return positions, guide means between the push buttons and the channel, adjustable actuating means carried by the push buttons and extending through the channel in alignment with the switch plungers, and yielding means between the push buttons and the channel to urge the push buttons to the released position.

3. In a switch actuating mechanism the combination with a panel having a vertical wall spaced from the face of the panel of a plurality of separate push buttons slidably mounted relative to the panel and movable between switch actuating and switch return positions, each push button having a threaded boss including radially extended grooves, motion transmitting means including a threaded stud extending through said vertical wall, yielding means between the push buttons and said vertical wall to urge the push buttons to the switch return position, and locking means between the stud and push button including a washer constrained to rotate with the stud and having axially extending projections adapted to project into the radial grooves formed in the

boss of its associated push button to restrain the stud from rotating relative to the push button until subjected to a force sufficient to compress the yielding means between the push button and the vertical wall of the channel.

4. In a switch actuating mechanism the combination with a plurality of separate switches of the push and return type having movable plungers, a bracket supporting said switches with their plungers in parallel relation, of a panel spaced from and carried by the bracket and including a channel shaped portion having upper and lower horizontal walls and a vertical wall, a plurality of separate push buttons slidably mounted in the channel and movable between switch actuating and switch return positions, each push button having a threaded boss including radially extended grooves, guide means between the push buttons and the lower wall of the channel, yielding means between the guide means and the push buttons to urge the push buttons into engagement with the upper wall, motion transmitting means including a threaded stud extending through the vertical wall of the channel in alignment with the switch plungers, yielding means between the push buttons and the vertical wall of the channel to urge the push buttons to the switch return position, and locking means between the stud and push button including a washer constrained to rotate with the stud and having axially extending projections adapted to extend into the radial grooves formed in the boss of its associated push button to restrain the stud from rotating relative to the push button until subjected to a force sufficient to compress the yielding means between the push button and the vertical wall of the channel.
